UNITED STATES PATENT OFFICE.

CLYDE J. COLEMAN, OF NEW YORK, N. Y., ASSIGNOR, BY MESNE ASSIGNMENTS, TO VIRGINIA REFRIGERATOR CORPORATION, A CORPORATION OF VIRGINIA.

REFRIGERATING APPARATUS.

1,102,998.

Specification of Letters Patent.

Patented July 7, 1914.

Application filed October 22, 1901, Serial No. 79,502. Renewed July 26, 1913. Serial No. 781,381.

To all whom it may concern:

Be it known that I, CLYDE J. COLEMAN, a citizen of the United States, residing at the borough of Manhattan, city of New York, in the county of New York and State of New York, have invented certain new and useful Improvements in Refrigeration Apparatus, of which the following is a specification, reference being had therein to the accompanying drawing.

My invention consists in the provision of automatic means connected with the condenser for removing uncondensable gases from a refrigerating system, and in the provision of pressure actuated means for such purpose and in the provision of coacting pressure and temperature actuated means for such purpose, and in the provision of such means at the exit end of the condenser.

My invention further consists in various improvements in the construction and combination of parts.

I will now describe the constructions of refrigerating apparatus illustrated in the accompanying drawings, and will thereafter point out my invention in claims.

The accompanying drawings, forming part hereof, illustrate constructions of refrigerating apparatus embodying my invention. I will now particularly describe such constructions and will thereafter point out my invention in claims.

Figure 1 is a sectional elevation of a complete refrigerating apparatus. Fig. 2 is an enlarged sectional elevation of the valve mechanism. Fig. 3 is an enlarged side elevation of the valve mechanism. Fig. 4 is a sectional elevation of a condenser with a modified form of blow-off valve.

The apparatus shown in the drawings is designed for the employment of a power medium, which may be water, and of a refrigerating medium, which may be ethyl chlorid, and the apparatus in the embodiment of my invention shown in the accompanying drawings and particularly claimed herein comprises means for circulating each of these mediums in a closed circuit or cycle.

The main parts of the power medium circulating means comprise a boiler or vaporizer 1, a compressor 2, and a condenser 3. The compressor may be said to be common to both circuits in that it has a movable separator or piston 4, which is caused to recip-

rocate by variations of relative pressure in a power medium chamber below the piston or separator and a refrigerant medium chamber above the piston or separator. The main parts of the refrigerating medium circuiting means comprise, in addition to the compressor, a condenser 5, a final condenser 55, and a cooling chamber 6.

The application of heat to the vaporizer or boiler is shown as accomplished by a gas burner 7, the gas supply to which is regulated by a thermostatic regulator 8, having a bulb 9 exposed within the vaporizer or boiler, and the thermostatic regulator acts automatically to diminish the supply of combustible gas to the flame when the temperature in the vaporizer or boiler rises above a predetermined point. The boiler receives its supply of power medium from the condenser 3 through a static column 70 conduit 10, which feeds the condensed fluid and is of sufficient height to overcome the difference of pressure between the condenser 3 and the boiler 1, and as there would be practically no pressure in the condenser 80 the static column would have to be of sufficient height to overcome the working pressure of the boiler. An automatic valve is provided for regulating the inflow of condensed power medium from the static column 85 to the boiler, comprising a float actuated valve 11, located in a chamber 12 alongside of the boiler so as not to be affected by the ebullition within the boiler, and connected to the boiler above and below the fluid level so that its fluid level will correspond with that of the boiler, and the static column conduit 10 is carried downward a substantial distance below this level to prevent any entrance of vapor into this 95 conduit from the vaporizer or float chamber. The float 13 of the float valve 11 has a considerable advantage of leverage over the valve, the float being on a long arm and the valve stem connected to a short arm of the 100 float lever 14.

The expanded power medium passes out of the boiler and upward through the conduit 15 which leads to the compressor 2.

The compressor 2 is provided with a movable separator or piston 4, of relatively large diameter and shown as packed with heat insulating material, to prevent substantial interchange of heat between the two mediums, as the temperature of the power medium 110

will be much higher than that of the refrigerating medium. The piston 4 fits loosely within its cylinder 16, and a seal is effected between the power medium chamber below the piston and the refrigerant medium chamber above the piston by means of a downwardly extending shell or skirt 17, which projects from the piston and enters an elongated annular well formed in a lower extension of the cylinder and dips within a body of fluid, such as mercury, located therein, the annular well being only sufficiently large to permit the skirt 17 of the piston to move freely therein and with a comparatively thin annular column of mercury on each side thereof. The difference in pressure between the power medium chamber and the refrigerant medium chamber of the compressor will not at any time be very great, and therefore the mercuric columns will have only a small movement, and I have provided an annular reservoir 18 located at the upper part of the inner wall of the annular well to retain a considerable body of mercury and prevent overflowing, and also to prevent material variation of level as the result of the variation in displacement by the skirt of the piston.

An intake valve 19 and an exhaust valve 20 are provided for the power medium, the intake valve 19 being located at the upper end of the conduit 15 from the boiler 1, and the exhaust valve 20 being located at the upper end of a conduit 21 leading from the compressor to the power medium condenser 3. These valves are automatically actuated by the movement of the piston through an actuating rod 22, located in an elongated pocket within the piston and having a knob 23 at its upper end adapted to be actuated by contact with the piston at the upper and lower end of the pocket therein and extending downward and pivotally connected to an arm 24 of the controlling weighted lever 25. The actuating rod is operated as the piston approaches the lower end of its stroke by contact of the knob 23 with the upper end of the pocket in the piston and moves downward a sufficient distance to swing the weighted lever 25 so that its center of gravity will be moved beyond its pivotal center, and so that it will fall by gravity to its right hand extreme position. The actuating rod is operated by contact of its knob 23 with the lower end of the pocket in the piston as the piston approaches the upper end of its stroke and swings the weighted lever 25 to the left, and sufficiently so that its weight will carry it to its extreme left hand position.

This actuation of the weighted lever 25 at each extremity of the movement of the piston operates the intake and exhaust valves through a sector 26 secured upon a shaft 27 and having contact pins 28 and 29,

the shaft 27 having secured thereon the two cams 30 and 31, the cam 30 being arranged to coact with the stem of the intake valve 19 to open the intake valve when the sector 26 is swung to the right, and the cam 31 coacting with the stem of the exhaust valve 20 to open the exhaust valve when the sector 26 is swung to the left. The intake valve is provided with a light spring 32 which tends to hold it closed, and the pressure of the motive medium also, and more powerfully, tends to hold it closed. The exhaust valve 31 is also provided with a light spring 33 which tends to hold it closed, and the pressure within the power chamber of the compressor also, and more powerfully, tends to hold it closed. The cams 30 and 31 are so constructed that one valve is closed before the other valve is opened. In the position of parts shown in the drawings, the exhaust valve has been closed and the intake valve opened and the piston is about to move upward.

The refrigerant medium in its cycle of movements is withdrawn from the cooling chamber by the compressor through the conduit 34 and enters the refrigerant medium chamber of the compressor through an intake check valve 35 and is forced out of the compressor chamber through an outlet check valve 36, both these check valves being represented diagrammatically in the drawings, and is forced from the compressor into the refrigerating medium condenser 5, and from the condenser 5 it passes through the conduit 37, including the final condenser 55, counter-currently to the refrigerant medium flowing from the cooling chamber to the compressor, the conduit 34 from the cooling chamber being shown as including the outer part of the final condenser, enveloping the part of the conduit 37 in such final condenser. The conduit 37 leads into the cooling chamber, and the flow of refrigerating medium from this conduit to the cooling chamber is regulated by an automatic float valve 38 located in a reservoir 39, interposed in the conduit 37, and having a float 40 arranged so as to have considerable advantage of leverage over the float valve 38 and operating to prevent the passage of any refrigerating medium into the cooling chamber until it has condensed to a liquid condition, and a sufficient quantity of condensed liquid has collected in the reservoir 39 to lift the float 40 and open the float valve 38.

In the operation of a closed cycle refrigerating system a certain quantity of foreign gases is usually produced, through chemical decomposition and otherwise, and these foreign gases, being uncondensable, remain in the condenser and interfere with and impede the condensing operation, diminishing the effective surface of the condenser. Under certain conditions a sufficient quantity

of these uncondensable gases may collect and accumulate in the condenser to nearly or entirely fill it and thus effectually prevent the performance of its condensing operation.

5 I have provided automatic means for the removal of uncondensable gases from the system and these means are shown as connected to the system in proximity to the exit end of the final condenser, at which 10 point the collection of these gases will be initiated.

In the refrigerating system shown the pressure within the condenser will be at all times, when the system is in operation, 15 higher than that of the atmosphere, and I have therefore provided a blow-off valve 41 for the removal of these uncondensable gases.

In the modified construction shown in 20 Fig. 4, the most simple form of this blow-off valve is illustrated, the blow-off valve as here illustrated being controlled by a weighted lever 42 which is set to open the valve when a pressure higher than the predetermined working pressure of the system has 25 been attained.

As the accumulation of uncondensable gases in the condenser will introduce a back pressure, any material accumulation of 30 these gases will sufficiently increase the internal pressure to cause the blow-off valve to be opened, and as this valve will be opened at the point of initial collection of these gases, and as the escape of these gases 35 will restore the normal pressure, this simple device may be relied upon in many constructions embodying my invention. I have, however, provided for a joint pressure and temperature regulated means for removing 40 uncondensable gases, and this construction is illustrated in the main views of the drawings, and is the particular construction herein claimed.

The blow-off valve 41 is here shown as 45 held normally closed by a spring 43, but this spring is sufficiently strong to hold the blow-off valve closed notwithstanding an increase of internal pressure above the normal, although it may be relied upon in the event 50 of failure of the temperature and pressure controlled means hereinafter described to relieve the system from a very considerable accumulation of uncondensable gases. The actuating means to open this blow-off valve 55 are shown as comprising an electro-magnet 44, the armature 45 of which is secured to the blow-off valve. The electro-magnet is energized from a battery 46 on normally open circuit, the circuit being held normally 60 open between the contact point 47 and the end of a bi-metallic thermostat 48; and the contact point 47 is located on a stem 49 secured at its upper end to a pressure actuated diaphragm 50 which is exposed to 65 the pressure within and in proximity to the

exit end of the final condenser. A spring 51 is shown as coiled about the stem 49 and abutting against a bracket 52 and against the lower end of the stem 49, to assist the resilient action of the diaphragm or to provide a resilient action should the diaphragm 70 be non-resilient.

The function of the thermostat 48 is to move away from the contact point 47 with an increase of temperature in the condenser. The function of the diaphragm 50 is to move the contact point 47 into contact with the thermostat with an increase of pressure in the condenser. Therefore the coaction of these devices results in the making of such contact at a higher pressure when the temperature of the condenser is higher and at a lower pressure when the temperature of the condenser is lower. The working temperature of the condenser is usually a variable 80 quantity by reason of the fact that the cooling water or heat abstracting medium is not usually regulated as to temperature, and is therefore subject to the variations of temperature at different seasons of the year, and from many other causes, or where cooling water is dispensed with and air is the cooling medium, the variations in the temperature of the air will produce variations in the working temperature of the condenser. 85 With a higher working temperature in the condenser, a higher pressure should be present therein in order to effectually condense the refrigerating medium. It will therefore be seen that with this construction, 90 the blow-off device is self-adjusting to these variations of working temperature due to external causes and the controlling device may be so constructed as to maintain a pressure within the condenser suited to its working temperature, and so that the blow-off device will not operate until this working 95 pressure has been exceeded.

It is evident that various modifications may be made in the constructions above described and shown in the drawings within the spirit and scope of my invention.

What I claim and desire to secure by Letters Patent is:

1. A refrigerating system comprising a condenser, a cooling chamber, means for circulating a refrigerant medium through the condenser and cooling chamber and in a closed cycle and for establishing difference of pressure between the condenser and cooling chamber, pressure actuated means exposed to the pressure of the condenser and temperature actuated means exposed to the temperature of the condenser, and means for the removal of uncondensable gases 115 from the system controlled by the coaction 120 of such devices.

2. A refrigerating system, comprising a condenser having a chamber at the exit end thereof, a cooling chamber, a conduit from 125

- the exit chamber of the condenser to the cooling chamber, means for circulating a refrigerant medium through the condenser and cooling chamber and for establishing 5 difference of pressure between the condenser and cooling chamber, means connected with the exit chamber of the condenser for the removal of uncondensed gases automatically operable on the attainment of a predetermined pressure and electrically operable supplemental actuating means therefor, and temperature operative means and pressure operative means adapted to coact with each other to control the electrically operable 10 means.
3. A refrigerating system, comprising a condenser having a chamber at the exit end thereof, a cooling chamber, a conduit from the exit chamber of the condenser to the 15 cooling chamber, means for circulating a refrigerant medium through the condenser and cooling chamber and for establishing difference of pressure between the condenser and cooling chamber, means connected with the exit chamber of the condenser for the removal of uncondensed gases automatically operable on the attainment of a predetermined pressure and electrically operable supplemental actuating means therefor, and 20 temperature operative means and pressure operative means adapted to coact with each other to control the electrically operable means.
4. A refrigerating system comprising a condenser, a cooling chamber, means for circulating a refrigerant medium through the condenser and cooling chamber and in a closed cycle and for establishing difference 25 of pressure between the condenser and cooling chamber, pressure actuated means exposed to the pressure of the condenser and temperature actuated means exposed to the temperature of the condenser near the exit end thereof, and means for the removal of uncondensable gases from the system controlled by the coaction of such devices.
5. In a refrigerating apparatus, in combination, a condenser, a cooling chamber, means for circulating a refrigerant medium 30 through the condenser and cooling chamber and establishing a difference of pressure between the condenser and cooling chamber, a pressure actuated device exposed to the pressure of the condenser, a thermostat exposed to the temperature of the condenser, 35
- circuit closing means controlled by such devices for closing an electric circuit by the relative movements thereof, and electrically operated means for the removal of gases from the condenser controlled by such circuit. 40
6. In a refrigerating apparatus, in combination, a condenser having a chamber at the exit end thereof, a cooling chamber, a conduit from the exit chamber of the condenser to the cooling chamber, means for circulating a refrigerant medium through the condenser and cooling chamber and establishing a difference of pressure between the condenser and cooling chamber, a blow-off valve connected to the exit chamber of the condenser and electrically operable supplemental actuating means therefor, and temperature and pressure operative means adapted to coact with each other to control 45 the electrically operable means.
7. In a refrigerating apparatus, in combination, a condenser, a cooling chamber, means for circulating a refrigerating medium through the condenser and cooling chamber and establishing a difference of pressure between the condenser and cooling chamber, a pressure actuated device exposed to the pressure of the condenser, a thermostat exposed to the temperature of the condenser, 50 circuit closing means controlled by such devices for closing an electric circuit by the relative movements thereof, a blow-off valve connected to the condenser, and electrically controlled means controlled by such circuit and controlling such blow-off valve.
8. A refrigerating system, comprising a condenser, a cooling chamber, a conduit from the condenser to the cooling chamber, means for circulating a refrigerating medium through the condenser and for establishing difference of pressure between the condenser and cooling chamber, and automatic means connected with the exit chamber of the condenser for the removal of uncondensable gases from the chamber such means including temperature and pressure actuated means adapted to coact with each other. 55
